LIQUID DISPENSER FOR A SURFACE TREATING MACHINE

Raymond Descarries, Montreal, Quebec, Canada, assignor
to Aktiebolaget Electrolux, Stockholm, Sweden, a cor-
poration of Sweden

Filed Sept. 22, 1960, Ser. No. 62,240

Term of patent 14 years

Claims priority, application Canada Aug. 31, 1960

(Cl. D9—2)

FIG. 1

FIG. 2

FIG.3

FIG.4

FIG.5

FIG. 1 is a front elevational view of a liquid dispenser for a surface treating machine, showing my new design;

FIGS. 2 and 3 are, respectively, rear and side elevational views thereof; and

FIGS. 4 and 5 are, respectively, top and bottom plan views thereof.

The dominant features of my design reside in the portions shown in full lines.

I claim:

The ornamental design for a liquid dispenser for a surface treating machine, as shown and described.
